UNITED STATES PATENT OFFICE.

EDGAR L. TRENTESSEAU, OF BOSTON, MASSACHUSETTS.

NIGHT LAMP.

Application filed March 10, 1922. Serial No. 542,657.

To all whom it may concern:

Be it known that I, EDGAR L. TRENTESSEAU, a citizen of the United States, residing at Boston, in the county of Suffolk and

5 State of Massachusetts, have invented certain new and useful Improvements in Night Lamps; and I do hereby declare the following to be a full, clear, and exact description of the invention, such as will enable others skilled in the art to which it 10 pertains to make and use the same.

This invention relates to lamps and more particularly to the type of lamps utilizing liquid fuel and embodying a fount and a 15 burner connected to the fount by means of a tube.

Other objects and advantages will be apparent and suggest themselves as the nature of the invention is understood.

20 While the drawings illustrate an embodiment of the invention it is to be understood that in adapting the same to meet different conditions and requirements, various changes in the form, proportion and minor 25 details of construction may be resorted to without departing from the nature of the invention.

Referring to the accompanying drawings forming a part of the application,

30 Figure 1 is a side view of a lamp embodying the invention.

Figure 2 is a front view of the fount or reservoir, the burner being omitted and the tube being in section, and

35 Figure 3 is an enlarged section of the burner.

Corresponding and like parts are referred to in the following description and designated in the several views of the drawings 40 by like reference characters.

The numeral 1 designates the fount, reservoir or container for holding the oil and while the same may be of any construction and design, it is preferred to have the same 45 represent a torch which is symbolical of cheer, hope and light. The rear side of the fount 1 is flat, as indicated most clearly in

Figure 1, so as to lie close against a wall or analogous support. The base of the fount is 50 likewise flat to admit of supporting the same upon a table or like part. An eye 2, at the upper end of the fount 1, provides

means for suspending the lamp from a nail or like part driven into a wall or other support. The filling opening, which is at the 55 top of the fount 1, is closed by means of a plug 3 in which is formed a vent opening. The fount may be constructed of any desired material.

A tube 4 leads from a side of the fount 60 adjacent the bottom thereof and extends laterally a short distance, thence vertically, its upper end being threaded as indicated at 5. The horizontal portion of the tube 4 is disposed so as to touch the table or like support upon which the lamp may be placed. This is indicated most clearly in Figure 1. A wick 6 fills the tube 4 and is of a length 65 to enter the fount and to project slightly beyond the upper end of the tube 4.

The burner comprises a tube 7, disk 8 and shade holder 9, said parts being connected in any preferred way. The tube 7 is threaded to receive and match the threaded portion 5 of the tube 4. Rotation of the burner upon the tube 4 covers or uncovers the projecting end of the wick 6, whereby the light may be regulated or extinguished. A shade 10, of any design, is fitted to the holder 9 and protects the light and increases the 70 draft so as to prevent smoking in a manner well understood. As indicated most clearly in Figure 1, the burner terminates about in line with the top of the fount 1, although this is not necessary.

85 It is observed that the tube 4 contains a single bend only. This facilitates the introduction of the wick when passing the same through the tube, when priming the lamp for service. It is further noted that the wick may be adjusted with ease when required so that a portion may project beyond the tip of the tube adjacent the burner, whereby provision is had for regulating the light as required. As the tube 4 communicates with the bottom of the fount 1, the consumption of the entire supply of oil in the fount is assured.

90 What is claimed is:

1. In a lamp of the character specified, a 100 tube having its upper end portion externally screw threaded, a wick within the tube, and a burner comprising a threaded tube mounted upon the threaded end of the

wick tube and adjustable thereon for regulating the light or extinguishing the same.

2. A lamp of the character specified comprising a tube having its upper end portion externally screw threaded, a wick within the tube, and a burner comprising a disk, a shade holder and a threaded tube and mounted upon the threaded portion of the

wick tube and adjustable thereon for regulating or extinguishing the light. 10

In testimony whereof I affix my signature in presence of two witnesses.

EDGAR L. TRENTSEAU.

Witnesses:

AUGUSTO E. RABUFFETTI,

WILLIAM J. REARDON.
